UNITED STATES PATENT OFFICE.

HARRY M. SCEARCE, OF NOBLESVILLE, INDIANA, ASSIGNOR TO THE NOBLESVILLE SPECIALTY COMPANY, OF NOBLESVILLE, INDIANA, A CORPORATION.

FILING APPARATUS.

No. 918,919.

Specification of Letters Patent.

Patented April 20, 1909.

Application filed March 26, 1908. Serial No. 423,481.

To all whom it may concern:

Be it known that I, HARRY M. SCEARCE, of Noblesville, county of Hamilton, and State of Indiana, have invented a certain 5 new and useful Filing Apparatus; and I do hereby declare that the following is a full, clear, and exact description thereof, reference being had to the accompanying drawings, in which like numerals refer to like 10 parts.

The object of this invention is to provide an improved filing apparatus, suitable especially for grocers and others who furnish duplicate invoices with each sale of goods in 15 a retail store.

While the device herein shown and described is a form of my invention suitable for grocers, especially, I do not wish to limit it to any particular class of filing, as it may 20 be used in various places and by various persons requiring the peculiar filing for which this is provided.

One feature of the invention consists in combining with a suitable cabinet a very 25 compact removable filing device, which may be operated within the cabinet during the day and at the end of the business hours the filing device may be readily lifted out of the cabinet and placed in a safe or vault of the 30 grocer over night and in the morning replaced in the cabinet for use. This enables the merchant to keep his duplicate invoices in a safe place over night without the necessity of removing the entire cabinet and apparatus.

Another feature of the invention consists 35 in the peculiar construction and arrangement of the parts of the filing device which are located in the cabinet. To that end a series 40 of rigid filing sheets are pivotally connected at their ends to a shuttle-shaped support which is pivotally mounted, so that as the filing sheets are lifted and turned from a horizontal to a vertical position for filing 45 invoices, the oscillatory support for the filing sheets will oscillate or rock to some extent and accommodate itself to the changing positions of the filing sheets. This is of particular value when there is a vertically ex- 50 tending back support for the filing sheets as they are turned into upward positions, as the oscillatory support will always hold the lower ends of the filing sheets at such 55 positions that the filing sheets when turned to their upper positions will incline rear-

wardly against the back support and remain there by gravity. Hence, all the filing sheets are held in their two positions, whether it be the upper or lower position, by gravity and without any particular attention on the part 60 of the operator.

Another feature of the invention consists in the combination of the filing device and the cabinet, whereby the filing device may be readily inserted or removed and be easily 65 operated in the cabinet. To that end, in order to reduce or diminish the size of the cabinet, the filing device is mounted upon the spring-supported means or plate, the spring being adapted to maintain such means 70 or plate in a horizontal position when the cabinet is open but when the top of the cabinet is folded down, said supporting means or plate may be depressed as the filing device is forced downward by the top of the cabinet 75 while closing it. Coöoperating with the spring for holding the supporting means or plate in position there is provided a chain or connection between said supporting means, or plate and the folding top of the cabinet, 80 whereby as the folding top is opened up it will through said connection lift the supporting means or plate to a horizontal position and when the top is folded down, said connection will permit the filing device to 85 move downwardly at the same time.

Another feature of the invention consists in the combination of a cabinet with an opening door or top, a filing device mounted therein and a slideable drawer also mounted 90 in said cabinet and adapted to be locked in connection with the door or lid whereby one lock will lock the whole.

Another feature of the invention consists in providing with the cabinet and filing device, a sliding arm-rest to use while writing invoices or the like on the filing sheets and which, when the device is closed up, constitutes a cover or top or closing part of the drawer.

The full nature of this invention will be understood from the accompanying drawings and the following description and claims.

In the drawings Figure 1 shows an elevation of the right hand side of the apparatus, the open position of the drawer being shown by dotted lines. Fig. 2 is a central vertical section longitudinally through the device when the forward part of the top is open but before the top is fully opened for use, show-

ing the arm-rest and drawer closed. Fig. 3 is a cross section through the apparatus on the line 3—3 of Fig. 1. Fig. 4 is a central vertical longitudinal section through the apparatus, showing it in use, with the drawer and arm rest, partially drawn out. Fig. 5 is a horizontal section on the line 5—5 of Fig. 1, parts being broken away. Fig. 6 is a vertical section through one of the filing sheets and showing some invoices filed. Fig. 7 is a perspective view of one end of the filing sheet support shown in modified form. Fig. 8 is a side elevation of one of the spring bearings upon which said modified form is mounted, and a vertical section through the plate that supports the filing device. Fig. 9 is a vertical section through the device on the line 9—9 of Fig. 4, parts being broken away.

The cabinet 10 constituting a part of the apparatus has a plain bottom and a plain rear end, and a board 11 on the upper side near the rear end, and sides with the rear half of their upper edges horizontal and the forward half inclined downwardly to the front as shown in Fig. 1. The top or lid consists of two portions, the front portion 12 which at its rear edge at 13 is hinged to the rear part of the top 14 that at its rear edge at 15 is hinged to the board 11, as appears in Fig. 1. The front part 12 of the top has downwardly depending front and side pieces that fit down upon the other parts of the cabinet and make the entire cabinet a parallelogram.

In the lower front part of the cabinet a drawer 16 is arranged slidably and members 17 of a lock are provided on the front ends of the drawer and folding top portion 12 so that when the drawer is pushed in and the top portion folded down the parts will be locked.

In the forward portion of the cabinet an arm rest or plate 18 is slidably mounted about midway between the top and bottom. It lies immediately over the drawer. The cross plate 19 is rigidly secured to the sides of the cabinet and at the rear end of the sliding arm rest, as shown in Figs. 2 and 4. To this stationary plate 19 a rearwardly extending plate 20 is hinged by spring hinges 21, the spring hinges being so arranged as to tend to support said plate 20 in a horizontal position and to permit it to yield downwardly. There is also a pair of cords or chains 22 extending from the sides of said plate 20 to the sides of the folding top portion 14 and attached to the latter at a point some distance forward of the hinges 15 and so arranged that when the top of the cabinet is elevated to the open position, as shown in Fig. 4, the chains 22 will elevate and hold the plate 20 in a horizontal position, but as the top is folded down, said chains will permit the plate 20 to move downwardly. The chains 22 accomplish the same object as the

it preferable to use both but either one will perform the function of elevating the plate 20.

The filing device consists of rigid filing sheets 25, preferably formed of aluminium, which sheets at two corners are pivoted to the oscillatory or rocking support 26 for said sheets. This support is made of two shuttle-shaped end plates secured together by an intermediate bar or plate 27 extending transversely of the device. The filing sheets have pins 28 extending laterally from each lower or inner end that project into the holes 29 in the supports 26, see Figs. 7 and 9. This enables the filing sheets to be turned from a substantially horizontal to a substantially vertical position but in order that they may stand up in the open position the arrangement is such that they may be turned back with their upper ends resting against the top portion of the cabinet when in its open or vertical position, as shown in Fig. 4. Therefore the support for the filing strips is oscillatably mounted in the cabinet at a point forward of the hinged connection between the folding top portion 14 and the top of the cabinet, as seen in Fig. 4. This enables the filing sheets to be tipped back into an inclined position so that they will be held open by gravity. There are fingers 30 or other filing means secured to each side of the filing sheets, as shown in Fig. 6. There may be any number of these fingers or paper catchers secured to each sheet on both sides and used for different customers. There are several invoice sheets 31 shown filed in Figs. 5 and 6.

The filing device may be supported by inwardly extending pins 40 from ears or plates 41 extending upwardly from the sides of the supporting plate 20, said pins adapted to extend through slots 42 in the shuttle-shaped plates 26, whereby the filing device may be readily removed or put in place in the cabinet. The filing device is mounted in a cabinet substantially as shown in Fig. 2, the fulcrum points of the filing sheets being in oval lines extending over and to the front of the fulcrum of the supporting means. As filing sheets are thrown up into the position shown in Fig. 4 the support 26 will gradually oscillate, the top end thereof turning toward the rear so that it would be possible to turn all of the filing sheets to their upper positions and if this were done the forward end of the support 26 would be in almost a horizontal line with the fulcrum thereof and therefore in a position above and to the rear of the position occupied by it when all of the filing sheets were turned down to the position shown in Fig. 2.

The modified form of mounting the filing device, shown in the last three figures, consists in providing upwardly extending ears 50 from the sides of the supporting plate 20 that are made of spring metal and their up-

per portions bent inwardly, as shown in Fig. 9 and provided with the slots 51 to receive pins 52 that extend laterally from the centers of the support and plates 26. In other words, this modified form is substantially the reverse of the form first described excepting that in the modified form the ears 50 are springs.

To reduce the vertical dimensions of the cabinet the filing device is mounted on the downwardly yielding plate 20 and therefore when the top of the cabinet is closed down the portion 14 thereof engages the rear part of the filing device and pushes it and the plate 20 downwardly to the position shown in Fig. 2; but when the device is taken out and opened up for use the filing device and plate 20 regain their upper positions, as shown in Fig. 4.

20 What I claim as my invention and desire to secure by Letters Patent is:

1. A filing apparatus including a cabinet, rigid filing sheets, and a single support to which said filing sheets are pivoted, said support being mounted in said cabinet so it will rock and adjust itself as said filing sheets are turned.

2. A filing apparatus including a cabinet with an upper part adapted to be opened, rigid filing sheets, a support therefor to which said filing sheets are pivoted which support is removably-mounted in said cabinet, a drawer in the lower part of said cabinet, and means for locking the folding top and drawer, substantially as set forth.

3. Filing apparatus including a cabinet with a folding top, rigid filing sheets, a support to which said filing sheets are pivoted, and yielding means within said cabinet on which said filing sheet support is mounted whereby the filing sheets and the support therefor will yield when the top is folded down.

4. A filing apparatus including a cabinet with a folding top, a yielding plate in the rear part of said cabinet, a filing device mounted on said plate so that the same may move downwardly when the top is folded down, and a drawer in the lower forward end of said cabinet.

5. A filing apparatus including a cabinet with a folding top, rigid filing sheets, a spring-elevated plate within said cabinet, and a support to which said filing sheets are

pivoted that is mounted on said spring-elevated plate, the parts being so arranged that when the top is opened and said plate is elevated the filing sheet support will project beyond the top of the cabinet and when the top is folded down it will engage the filing sheet support and press it and said spring-supported plate downwardly.

6. A filing apparatus including a cabinet with a folding top, a filing device, means for supporting said filing device and which is hinged at one end within said cabinet, and a connection between said supporting means and the folding top arranged so that when the top is opened the filing device will be elevated and when the top is closed it will be lowered.

7. A filing apparatus including rigid filing sheets, a single support therefor to which the filing sheets are pivoted, said support being mounted so it will rock as the sheets are turned from a horizontal to a vertical position, and means to the rear of said support against which the sheets may rest when thrown to their upper positions.

8. A filing apparatus including rigid filing sheets, a support therefor to which the ends of the filing sheets are pivoted in a curved line, means for fulcruming said support substantially on lines between the ends of said series of pivotal connections, and means for stopping the upper rearward movement of the sheets as they are turned upward, whereby said support will rock toward said stopping means as the sheets are turned upwardly.

9. A filing apparatus including a cabinet with a folding top hinged near the rear end so that when folded upwardly it will extend substantially vertically, rigid filing sheets, a support to which said sheets at their inner ends are pivoted, and means for fulcruming said support between its front and rear ends at a point forward of the top when turned upwardly whereby said top will serve as a back rest for the sheets when turned upwardly, substantially as set forth.

In witness whereof, I have hereunto affixed my signature in the presence of the witnesses herein named.
